UNITED STATES PATENT OFFICE.

JOHN B. CROFOOT, OF ARLINGTON HEIGHTS, ILLINOIS.

STAPLE.

Application filed April 4, 1927. Serial No. 180,767.

My invention relates to improvements in staples, and more particularly to a staple strip which comprises a plurality or series of connected entire staple units and a mutilated final staple unit at the end of said strip.

The object of my invention is to provide perforated means on the staple units and particularly on the mutilated final unit to be engaged by the feed pawl of the stapling machine for the purpose of facilitating the positive and automatic expulsion of the mutilated final unit from the stapling machine, thereby preventing clogging of the machine and permitting the unhampered insertion of a new staple strip.

10

This application is a division of my pending application, Serial No. 65,270, filed October 28, 1925.

20 The invention will best be understood by reference to the accompanying drawing forming a part of this specification and in which,

Fig. 1 is an elevational view partly in 25 cross-section of a stapling machine showing an entire staple unit together with a mutilated unit of my improved staple strip in position in the machine.

Fig. 2 is a horizontal sectional view taken 30 on approximately the line 2—2 of Figure 1.

Fig. 3 is a plan view of part of a staple strip.

Fig. 4 is an end view of that disclosed in Figure 3.

35 In the accompanying drawing I have shown one form of my invention in position on a stapling machine 10 provided with a plunger 11 which has a slot with a cam face 12 on one side, for receiving and for actuating a bolt 13, thereby moving the feed pawl 14 forward and backward by the reciprocation of said pawl, in order to feed the strip 15, a unit at a time.

40 A hold back pawl 16 is pivoted on the frame of the machine and is spring-pressed 45 to engage the staple strip, and preferably to engage in an opening provided in said strip.

45 The staple strip 15 consists of a plurality 50 or a series of entire staple units 17 having pointed fingers 18 on each side, and a mutilated final staple unit 19 at the end of the strip, as best shown in Figure 3. Each of said staple units 19, as well as the entire 55 units 19, has perforations 20 provided on the back portion or main body portion there-

of for receiving the feed pawl 14, as best shown in Figure 2; and an opening 21 is provided in the connecting part or neck between a pair of adjoining units, and directly 60 across the line of cut or separation between said units, for receiving the hold back pawl 16 to prevent return movement of said staple strip when the feed pawl 14 moves rearwardly.

65 During the feeding of the staple strip, feed pawl 14 engages in openings 20 and feeds the forward unit into position under the plunger 11, as indicated in Figures 1 and 2, and when the last entire unit has been fed, the feed 70 pawl 14 engages back of the shoulders 19' at the rear end of the mutilated final unit, and when the plunger 11 has returned to its upper position, with the bolt 13 and feed 75 pawl 14 thereupon moved into their forward position, the engagement of pawl 14 against shoulders 19' will positively expel said final unit from the stapling machine.

By thus arranging the perforations 20 across the back or main body portion of the 80 staple unit, for receiving the feed pawl during normal feeding movements of the machine, instead of feed pawl engaging back of the side extension or legs of the staple units, the complete or entire units are fed 85 forwardly into the position shown in Figure 2, and upon the last stroke of the pawl is enabled to engage behind shoulders 19' and during its forward movement, to move the same sufficiently forward to tilt and positively expel said final unit from the machine. 90 (See unit 19 dotted in Figure 2.)

It is apparent from the above disclosure 95 that the strip and each staple unit therein has been so arranged and constructed that the pawls will hold the strip and also the final unit in position to facilitate proper 100 ejection of said final unit without any danger of said unit moving laterally or crosswise into the feed channel of the machine, or to 105 clog the feed channel therein in any manner, but instead the final unit 19 is held in position by the co-operation of the feed pawl engaging in openings 20 and the hold back pawl engaging in the semicircular opening 110 between the shoulders 19' until the feed pawl is moved rearwardly behind said shoulders and thereupon moves it straight forward, out of the machine.

While I have described the preferred form 110 of construction for carrying my invention into effect, this is capable of variation with-

out departing from the spirit of the invention. I do not, therefore, wish to be limited to the precise details of construction set forth, but desire to avail myself of such variations and modifications as come within the scope of the appending claims.

I claim as my invention:

1. A staple strip having a mutilated staple at one end thereof and provided with means arranged to be engaged by the feed mechanism of a stapling machine, whereby said mutilated staple is automatically and positively ejected from said machine.

2. A staple strip having a mutilated staple at one end thereof and integral therewith and provided with a feed shoulder arranged to be engaged by the feed mechanism of a stapling machine, whereby said mutilated staple is automatically and positively ejected from said machine.

3. A staple strip having a mutilated staple at one end thereof and integral therewith provided with rearwardly extending means arranged to be engaged by the feed pawl of a stapling machine, whereby said

mutilated staple is positively ejected from said machine.

4. A staple strip having a mutilated staple at one end thereof and provided with means, arranged at the rear of said mutilated staple, and perforations in said mutilated staple to be engaged by feeding pawls of a stapling machine, for positive and automatic ejection from said machine by said pawls.

5. A staple strip composed of a plurality of entire staple units, and having a mutilated staple unit at one end thereof; each unit having perforations in its back or main body portion, for normally receiving a feeding member of a stapling machine, said mutilated staple unit having shoulders extending rearwardly therefrom, for engagement with a feeding pawl of a stapling machine, for positive and automatic ejection from said machine, by said pawl.

In testimony whereof I have signed my name to this specification.

JOHN B. CROFOOT.
